Modern Curtain Co. Inc., Boston, Mass., a cor-
poration of Massachusetts

Application July 25, 1940, Serial No. 93,924

Term of patent 7 years

To all whom it may concern:

Be it known that I, Sidney S. Gutten, a citizen of the United States, residing at Newton, in the county of Middlesex and State of Massachusetts, have invented a new, original, and ornamental Design for a Curtain, of which the following is a specification, reference being had to the accompanying drawing, forming part thereof, wherein the figure is a front elevation of a curtain showing my new design.

The characteristic feature of my design for a tie-back curtain resides in a ruffled cornice having a contrasting stripe running lengthwise of said cornice and having superimposed on said stripe a streamer-bow of substantially the same width as said stripe, as shown.

I claim:

The ornamental design for a curtain, substantially as shown and described.

SIDNEY S. GUTTEN.
